PHONOGRAPH

Henry S. Carlson, West Orange, N. J., assignor to
 Thomas A. Edison, Incorporated, West Orange,
 N. J., a corporation of New Jersey

Application October 15, 1938, Serial No. 235,213

18 Claims. (Cl. 274—17)

This invention relates to phonographs, and more particularly to phonographs of the commercial type. An important aspect of the present invention is in the provision of a cabinet for a commercial phonograph wherein there are provided operative connections between the phonographs and the cabinet. In some respects the present invention relates to improvements over the copending application of Louis Z. La Forest, Serial No. 180,940, filed December 21, 1937, and entitled "Phonographs" (which application is now issued as Patent No. 2,203,096).

When commercial phonographs, or dictating machines, are made small and completely enclosed by cabinets closely fitting the phonograph for the purpose of rendering the phonograph readily portable and suitable for desk use, the ease of operation of the phonograph may be impaired unless the phonograph and cabinet are carefully designed and well adapted to each other.

One of the difficulties encountered with a cabinet of the abovementioned type lies in rendering the phonograph accessible for convenient operation with the use of a small closure which will closely fit the cabinet while the closure is in open position. As described in the abovementioned copending application, this difficulty has been circumvented by the provision of a plurality of closures. These closures may comprise a main cover and a pivotally mounted side closure which are separate of each other but which are interconnected for simultaneous opening and closing thereof. The improved means herein disclosed for interconnecting these closures is now described and claimed in my copending divisional application Serial No. 386,225 filed April 1, 1941.

A difficulty encountered when the phonograph and cabinet are made small, is in arranging the machine and cabinet so that the phonograph control means is readily accessible and of such size as to be easy to operate. An object of this invention is to overcome this difficulty by placing the control means into such spaced relationship with the cabinet that the range of movement thereof extends from within the cabinet to a position or positions beyond the cabinet.

With such arrangement of the control means there is, however, encountered the possibility of the operator moving the control means into a position outwardly of the cabinet, as during the use of the phonograph, and then inadvertently attempting to close the cabinet without first moving the control means into a position within the cabinet. It is an object of this invention to

avoid such difficulties by interconnecting the control means with a closure of the cabinet so that the control means is automatically moved into the cabinet as an incident of closing the same.

5 Another object is to provide a plurality of simultaneously controlled closures for a phonograph cabinet, which are coupled to a phonograph control means projecting beyond the cabinet so as to move the control means into a position within the contour of the cabinet as the cabinet is closed.

Other objects are to move a control means for the phonograph from an operative position beyond the cabinet into a neutral or inoperative position within the contour of the cabinet as the cabinet is closed, and to lock the control means against movement into a position beyond the cabinet while the cabinet is other than fully open.

15 20 It is a still further object of my invention to prevent possible extraneous movements of parts of the phonograph—the carriage, for example—as by a tilting of the phonograph during its transportation. A feature of my invention is to obstruct or lock the carriage against such movement when the cabinet is closed.

25 Still other objects and features will appear from the following description and the appended claims.

30 In the description of my invention reference is had to the accompanying drawings, of which: Figure 1 is a side elevational view of a phonograph cabinet in accordance with one embodiment of the present invention, parts of the cabinet being broken away for the better illustration of phonograph parts within the cabinet;

35 Fig. 2 is another side elevational view of the phonograph cabinet of Fig. 1, parts being broken away and the front and side closures being in their respective open positions to show the phonograph contained therein;

40 Fig. 3 is a partial top plan view of the cabinet and phonograph of the above figures, in which the upper wall portion of the cabinet is broken away to show in particular the supporting means for the closures of the cabinet;

45 Fig. 4 is a side elevational view of a portion of the phonograph, showing the control or shifting means for the translating device of the phonograph in a neutral or inoperative position;

50 Fig. 5 is a vertical cross-sectional view taken substantially along the line 5—5 of Fig. 1;

55 Fig. 6 is an enlarged detailed view of a portion of the phonograph and cabinet of the above figures, principally showing means operated by the

cover for obstructing the movement of the carriage;

Fig. 7 is a partial view in side elevation of the mechanism of Fig. 6;

Fig. 8 is a side elevational view, partly broken away and partly in section, of a phonograph and cabinet in accordance with another embodiment of my invention; and

Fig. 9 is a cross-sectional view taken substantially along the line 9—9 of Fig. 8.

Reference being had to the figures, particularly Figs. 1 and 2, there will be seen a cabinet 1 closely fitting a phonograph of the type commonly used for the recordation and reproduction of dictation. The lower portion 2 of the cabinet, comprising substantially the lower half thereof, is rectangularly shaped and preferably formed, as by casting, in an integral piece. Supported by the lower portion 2 is a base plate 3 hinged to the rearward wall 4 of the portion 2 and resting on a stud 5 provided on the forward wall 6 of the portion 2. The plate 3 has left and right upright standards of which the right standard appears as 7; these standards carry the front and back longitudinal rods 8 and 9 on which there is slidably mounted a carriage 10. The carriage 10 has an arm 11 extending forwardly above a cylindrical record 12 which is removably carried by a mandrel 13. Movement of the carriage 10, longitudinally of the record 12, may be effected by a driving means comprising a feed screw 14 (see Figs. 3 and 4), which is rotatably supported by the abovementioned standards and with which there is brought into engagement a feed nut 15 secured to a bracket 16 pivoted to the carriage by a pivot rod 17. When the feed nut 15 is in engagement with the feed screw 14, steady rotation of the feed screw will cause the carriage 10 to be steadily moved across the record 12. Such rotation of the feed screw 14, as well as rotation of the mandrel 13, may be effected by a suitable driving motor not herein necessary to be shown. When the feed nut 15 is, however, out of engagement with the feed screw 14, the carriage is freely movable at will along the record 12.

The carriage arm 11 carries a translating device 18 shiftable from an inoperative condition into respective operative conditions for recording and reproducing. When conditioned for recording, the translating device is adapted to receive sound waves by way of a tubular element 19 on the translating device, and impart a movement undulating in accordance with those waves to a recorder stylus 20, and, when conditioned for reproducing, to create sound waves in accordance with any undulating movement imparted to a reproducer stylus 21, as by the engagement of the reproducer stylus with a progressive modulated groove on the record 12.

The means for controlling the engagement of the feed nut 15 with the feed screw 14, and for shifting the translating device between inoperative and operative conditions may comprise a forwardly extending control or shifting lever 22 which is pivoted by a pivot screw 23 on a boss 23' provided on the right side of the carriage arm 11. The control lever 22 has a relatively short downwardly extending arm 22' which is connected, as by a link 24, to a block 25 provided within a hub portion 10' of the carriage 10 and embracing the rod 8, the link 24 being pivoted to the arm 22' by a pin 26 and to the block 25 by a stud 27 extending rightwardly of the block through an opening 28 at the right side of the carriage. Thus, as the control lever 22 is rocked upwardly

and downwardly from its inoperative position shown in Fig. 4, the block 25 is rocked in clockwise and counterclockwise directions about the rod 8. The block 25 is coupled to the translating device 18 as by a coupling means not herein necessary to be fully described. This coupling means is arranged so that movement of the control lever 22 from an inoperative position into the upward and downward positions shown in Fig. 2 (the downward position being shown in dash-dot lines) causes the translating device to be respectively conditioned for reproducing and recording, the conditioning of the translating device being effected as by a camming action between a cross pin 29 carried by the block 25 and the lifting arms 30 (fractionally shown in Figure 4). In moving the control lever into either of its operative positions, that is the upward or reproducing position and downward or recording position, the feed nut 15 is brought into engagement with the feed screw 14, as by a camming action between the pin 29 and an arm 31 on the bracket 16. Thus, when the control lever 22 is in an upward or reproducing position, the feed nut 15 is in engagement with the feed screw 14 and the translating device is conditioned for reproducing, the reproducer stylus 21 then being in engagement with the record 12; when the control lever is in a downward or recording position, the feed nut is again engaged with the feed screw but the translating device is conditioned for recording, the recorder stylus 20 then being in engagement with the record 12; but when the control lever 22 is in neutral or inoperative position, shown in Fig. 4, the feed nut is disengaged from the feed screw to render the carriage freely movable, at will, and the translating device is in an inoperative condition, both styli 20 and 21 then being out of engagement with the record 12.

In a preferred form of cabinet the upper portion is substantially arcuately shaped in cross section, as viewed from the end, and comprises a detachable rearward closure section 32, a forward closure or cover 33, and a movable side wall section or side closure 34. By having the upper portion of the cabinet arcuately shaped, sufficient accessibility may be provided to the front portion of the phonograph by the opening of the cover 33, which need not swing outwardly of the cabinet for opening movement but which may be pivotally mounted to swing upwardly within the rearward section 32. In such upward position, the cover 33 may conform closely to the walls of the rearward section 32 and thereby utilize very little of the interior space of the cabinet. The side closure 34 may be moved into an open position to provide access to the mandrel 13; in such open position the side closure 34 may conform closely to the walls of the cabinet and thereby also utilize very little of the interior space of the cabinet.

Since no access need be provided to the left side of the phonograph the cover 33 may be pivoted leftwardly thereof in any suitable manner not necessary to be herein shown. On the right side of the phonograph, however, there must be provided full access to the mandrel 13, and a form of pivotal mounting for the cover 33 must be used which will not interfere with such access to the mandrel. The cover 33 is therefore effectively pivoted by means of a sliding connection with the standard 7 of the phonograph. This sliding connection comprises an arcuately shaped member 35, formed as by stamping, made substantially equal to a half circle in length, and

provided with a channelled portion 36 extending throughout the length thereof. In the channelled portion 36, longitudinally thereof, there is provided a slot 37. Passing through the slot 37 and threading into the standard 7 are the shoulder screws 38, the heads 38' of which are disposed for sliding movement within the channelled portion 36. Thus, the arcuate member 35 is supported by, and effectively pivoted to, the standard 7.

The forward portion of the arcuate member 35 is secured to the cover 33 by means of a small lug 39 turned up from the member 35, and by means of a narrow strip 40 bent over from the inner wall 36' of the channelled portion 36, the lug and strip being each secured to the right-hand end wall 41 of the cover 33 such as by spot-welding indicated at 39'. The rearward portion of the strip is offset to the left along the line 42 and is provided with a cam 55 for reasons hereinafter explained. With the above-described means, the cover 33 is effectively pivoted to the standard 7 without obstructing the free end of the mandrel 13.

The side closure 34 is supported by front and back arm extensions 43 and 44. In order that this side closure may be in substantial alignment with the end wall 41 of the cover 33, to form in effect an extension of the wall 41 when the cover and side closure are in their respective closed positions, the arm extensions 43 and 44 are suitably offset to the left at the lines 43' and 44'. The front arm extension 43 is extended forwardly below the base plate 3, and is pivoted by a pin 45 to a downwardly extending arm 46 on the base plate 3. The back arm extension 44 is connected to the end wall 41 of the cover 33, inwardly thereof, by means of a headed pin 47 secured to the arm extension 44 and passing through an elongated slot 48 provided in the end wall 41 of the cover, the slot 48 being substantially radially disposed in relation to the pivot axis of the cover. Thus as the cover 33 is swung upwardly into open position and downwardly into closed position, the pin 47 slides inwardly and outwardly along the slot 48 to swing the side closure 34 downwardly and upwardly, about the pin 45, into its respective open and closed positions. Since the back arm extension 44 is connected to the cover 33 inwardly thereof, the strip 40 of the arcuate member 35 is suitably offset along the line 42, as hereinbefore explained, so that the arm extension 44 may be clear of the arcuate member 35.

Whenever a cabinet is closely fitted to a phonograph it may be found difficult to provide sufficient space for the free and easy operation of manually operable phonograph control means. In the phonograph hereinabove described, it has been found important that the control lever 22 be extended forwardly of the carriage arm 11 so that the control lever may be easy to operate, as by reason of the increased leverage obtained, and so that the operator may readily grasp the control lever without directing his attention thereto and without probability of striking his fingers against the record 12. When the control lever 22 is so lengthened, however, it is found that the control lever extends into the path of the cover 33 when the control lever is in its upward or reproducing position. Closing of the cover may thus be obstructed by the control lever. It is obviously undesirable to increase the overall size of the cabinet for the mere reason of providing sufficient space therein for a range of

movement of the control lever that is free of the path of the cover. In accordance with the present invention such need for enlarging the cabinet is overcome by the provision of simple means whereby the control lever 22 is moved into a position within the cabinet as an incident of closing the cover 33.

It will be understood that the embodiment of my invention illustrated in Figs. 1 to 7 inclusive 10 contemplates not only the movement of a manually operable control means to a position within the contour of the cabinet but also the movement of the control means into its neutral or inoperative position, to place the machine itself in an 15 inoperative condition, as an incident of closing the cabinet. More specifically, this embodiment of my invention is concerned with the type of control means which is active throughout a range of movement extending from within, or from the 20 contour of, the cabinet to positions outwardly of the cabinet, and it contemplates a one-way automatic movement of this control means, or more specifically, a movement of the control means into a position within the contour of the cabinet as a closure of the cabinet is moved to closed 25 position, but no movement of the control means as the closure is opened.

In order to effect, as an incident of closing the cover 33, a movement of the control lever 22 out of its reproducing position (wherein the control lever extends into the path of the cover 33) into its inoperative position (wherein the control lever is within the contour of the cabinet and out of the path of the cover), the rod 8 is mounted for turning movement thereof and the block 25 is splined to the rod 8 by means of a screw 49 threading into the block and slidably engaging a longitudinal slot 50 provided in the rod 8. The rod 8 is extended slightly to the right of the standard 7 and is there provided with an arm 51 which is secured to the rod 8 by means of a shoulder screw 52. Thus as the control lever 22 is moved upwardly and downwardly the arm 51 is rocked in clockwise and counterclockwise directions. Provided on the arm 51 is a rightwardly extending pin 53 which is arranged to engage with a cam surface 54 provided on the forward end of the inside wall 36' of the arcuate member 35. (The arm 51 may also, if desired, be provided with a downward extension 51' which is moved into a position to obstruct the mounting and removal of a record with respect to the mandrel 13, as the control lever 22 is moved into reproducing position.)

When the cover 33 is in open position, as shown in Fig. 2, the cam portion 54 is disposed rearwardly of the pin 53 and out of the range of movement of the pin. The control lever 22 may then be moved freely throughout its range of movement. Should the cover 33 be closed while the control lever 22 is in reproducing position, the initial closing movement of the cover will cause the cam portion 54 to impinge upon the pin 53 so as to move the arm 51 downwardly, thereby moving the control lever 22 out of the path of the cover into its inoperative position. Thus the control lever 22 is moved within the contour of the cabinet and the translating device 18 is rendered inoperative, as an incident of closing the cover 33. When the cover 33 is in other than a fully open position, any accidental attempt to move the control lever 22 upwardly, as into a position wherein the control lever 22 will interfere with the opening or closing of the cover, is prevented by the impingement of the

pin 53 against the wall 36' of the arcuate member 35. It will, however, be seen that the coupling between the control lever 22 and the cover 33 has a one-way action since the control lever 22 is not moved by the opening of the cover.

The machine of the type here described is compactly arranged to render it readily portable. If, however, in its transportation it should be tilted while the feed nut 15 is out of engagement with the feed screw 14, as when the control lever 22 is in inoperative position, the carriage may be moved back and forth on the rods 8 and 9 by its own weight. This possible extraneous movement of the carriage by its own weight is highly objectionable in that it may cause clashing of parts and possible damage to the phonograph. It is, however, a feature of my invention to avoid this possible damage to the phonograph by the provision of suitably controlled means for applying a braking action to the carriage so as to obstruct or lock the carriage against extraneous movements thereof. To effect this braking action I couple the carriage to a member which extends along the path of the carriage and which is stationary longitudinally of such path. It will, however, be understood that in accordance with my invention this member need not be necessarily stationary in the direction of movement of the carriage at all times so long as the member is stationary in the direction of movement of the carriage when the phonograph is out of operation. Since the phonograph cabinet is normally closed during its transportation, the means for obstructing or locking the carriage may be readily controlled by the cover of the cabinet.

In the embodiment of my invention illustrated in Figs. 1 to 7 inclusive, the carriage-obstructing means is of a friction type, this obstructing means being rendered operative when the cover 33 is closed and inoperative when the cover is open. This means for obstructing movement of the carriage by friction comprises a ridge 56 provided on the rod 9 throughout the length thereof. The rod 9 is pivotally mounted on the left and right standards of the phonograph and, as hereinbefore described, the carriage 10 is slidably mounted on the rod 9, the carriage being provided with a slot 57 which is engaged by the rod. When the rod 9 is turned, as in a counter-clockwise direction, the ridge 56 is caused to bear against the wall of the slot 57 so as to impede any movement of the carriage. The means for so turning the rod 9 comprises an arm 58 pivoted on the right end of the rod 9 adjacent to the inner wall of the standard 7. The arm 58 is resiliently connected to the rod 9 by a torsional spring 59 which is coiled about the rod 9 and hooked at its respective ends on a pin 60 carried by the arm 58 and on a short arm 61 carried by a collar 62 secured to the rod 9 by a screw 63 (see Figure 6). The spring 59 urges the rod 9 in a counter-clockwise direction with respect to the arm 58 but such relative movement of the rod 9 to the arm 58 is limited by the impingement of the arm 61 with a pin 64 provided on the hub 58' of the arm 58. When, however, the arm 58 is moved in a counter-clockwise direction the rod 9 is yieldably moved therewith so as to cause the ridge 56 to bear against the wall of the slot 57, thereby impeding by friction any movement of the carriage.

The rod 9 is so moved upon a closing of the cover 33 by the engagement of a rightwardly extending pin 65, provided on the arm 58 and

passing through an opening 66 in the standard 7, with a cam 55 comprising a turned-over piece on the strip 40 of the arcuate member 35. However, as the cover 33 is opened the cam 55 first

5 rides off of the pin 65 and then the arm 58 is moved in a clockwise direction by the engagement of a cam 67 with the pin 65, the cam 67 being provided on a bracket 68 which is spot-welded to the right end wall 41 of the cover 33.

10 As the arm 58 is so moved, the pin 64 impinges against the arm 61 to cause the rod 9 to be moved in a clockwise direction, thereby fully clearing the ridge 56 from the walls of the slot 57.

Thus in accordance with the first embodiment
15 of my invention, as the cover 33 is closed the control lever 22 is moved into its inoperative position wherein it is within the cabinet, as hereinbefore described, and a braking action is applied to the carriage 10 to obstruct a movement
20 of the carriage such as, for example, may be caused by a tilting of the machine; and as the cover is opened no movement is imparted to the control lever 22, but the braking action on the carriage is relieved.

25 In the second embodiment of my invention, illustrated in Figs. 8 and 9, the control lever 22 is moved, as an incident of closing the cover 33, from its operative position (wherein it extends beyond the contour of the cabinet) into its other operative position instead of into its inoperative position as in my first embodiment. By so doing there is avoided the requirement for auxiliary means to lock or obstruct the carriage against possible extraneous movements, since the feed
30 nut 15 with the feed screw 14, which are mutually engaged when the control lever is in operative position, constitutes a locking or movement-obstructing means for the carriage. It is, however, desirable that the control lever 22 be returned to inoperative position upon the opening of the cover in order to permit an immediate mounting of a record on the machine after the cabinet is opened. It is therefore a feature of my second embodiment to provide a coupling
35 between the cover 33 and control lever 22 having a two-way action, this action being such that the control lever is moved into recording position (the operative position of the lever which is within the cabinet) as the cover is closed and into inoperative position as the cover is opened.

40 The phonograph and cabinet of my second embodiment may be of the general form of my first embodiment. In the present instance, however, the inter-coupling between the cover 33 and back rod 9 is dispensed with and a modified form of arcuate member 35 is employed having the reference character 70. Furthermore the standard 7 and the back rod 9 of my first embodiment are slightly modified, principally in that they now respectively appear without the opening 66 and the ridge 56; these elements are therefore now given the respective reference characters 7a and 3a. Other elements which are in all respects similar to the corresponding elements of my first embodiment appear with the same reference characters.

45 At the right end of the rod 8 there is provided the arm 51 (having the downward extension 51'), the arm 51 carrying the rightwardly extending pin 53. By reason of the coupling between the rod 8 and the control lever 22, a rocking of one causes a similar rocking of the other. Thus when the control lever 22 is in its upper or reproducing position, the pin 53 is in an upper position, but
50 when the control lever 22 is rocked into its in-

termmediate and downward positions, corresponding respectively to its inoperative and recording positions, the pin 53 is moved into intermediate and downward positions as shown in dash-dot lines in Fig. 8.

The means for moving the control lever 22 into recording position as an incident of closing the cabinet comprises a curved track 69 provided on the end wall 41 of the cover. This track is arranged to engage the pin 53 and move it into its downward position to effect the recording condition of the machine as the cover 33 is moved into closed position. The track 69 may very conveniently be part of the aforementioned arcuate member 70 which effectively pivotally connects the cover 33 to the standard 7a in a manner in all respects similar to that of my first embodiment, the arcuate member being provided throughout its length with the channelled portion 36 having the longitudinal slot 37 through which passes the shoulder screws 38, as heretofore described. This track is provided along the upper half portion of the member 70 as shown in Fig. 8, and is open to the left as shown in Fig. 9; the track is also offset to the right with respect to the channelled portion 36 so that the track will clear the arm 51. The member 70 is secured to the cover 33 by spot-welding the bottom 69" of the track 69 to the end wall 41 of the cover, and by means of a lug 71 on the member which is secured to the end wall 41 of the cover also by spot-welding.

When the cover 33 is fully open the pin 53 is disposed in front of the upper portion 69' of the track 69, the pin 53 then being free to move into its respective positions corresponding to the operative and inoperative positions of the control lever 22. The upper portion 69' of the track is, however, flared out so that the track 69 will engage the pin 53, as the cover is closed, irrespective of the position of the pin 53 in its path. Proceeding along the track 69 from the upper or flared portion 69' thereof, the track first corresponds in position to that occupied by the pin 53 when the control lever 22 is in inoperative position, and then curves inwardly to a position corresponding to that occupied by the pin 53 when the control lever 22 is in recording position. If this inward curving of the track 69 is completed at an intermediate position along the track (such as position P in Fig. 8), the remaining portion of the track may be a simple arc about the axis of the cover. Thus as the cover 33 is closed the control lever 22 is moved into recording position irrespective of the position of the control lever in its path at the time the closing movement of the cover is started; and as the cover is opened the control lever 22 is returned to inoperative position. It is for the reason of returning the control lever 22 to inoperative position as the cover is opened that the portion of the track 69 immediately behind the flared portion 69' of the track is positioned to correspond to the intermediate position of the pin 53.

Although I have described and illustrated my invention in several embodiments, it will be understood that many other forms and modifications of the same may be employed without departing from the scope of my invention, which I undertake to express according to the following claims.

I claim:

1. In a structure comprising a cabinet containing a phonograph: in combination, an openable and closeable cover for said cabinet; a mov-

ably mounted carriage on said phonograph; carriage-locking means; and means, operatively connecting said cover with said carriage-locking means and controlled by the cover when the same is moved between open and closed positions, for operating said carriage-locking means.

2. In a structure comprising a cabinet containing a phonograph: in combination, a closure for said cabinet having open and closed positions; a driving means for said phonograph; a movably mounted carriage connectable with said driving means and normally freely movable when disconnected therefrom; means operable to obstruct said carriage against movement; and means, operated by said closure, for causing said carriage to be disconnected from said driving means and concurrently causing said carriage-obstructing means to be rendered operative.

3. In a structure comprising a cabinet containing a phonograph: in combination, an openable and closeable cover for said cabinet; a movably mounted carriage on said phonograph; a member extending along the path of said carriage and stationary longitudinally of said path; and means, controlled by said cover, for coupling said carriage to said stationary member.

4. In a structure comprising a cabinet containing phonograph: in combination, an openable and closeable cover for said cabinet; a movably mounted carriage on said phonograph; carriage-moving means operable at will and unmovable in the direction of movement of said carriage at least while out of operation; means operable to couple said carriage with said carriage-moving means; and means, operated by the opening and closing of said cover, for respectively rendering said coupling means inoperative and operative.

5. In a structure comprising a cabinet containing a phonograph: in combination, a movable cover for said cabinet; a movably mounted carriage on said phonograph; friction means movable into operative relationship with said carriage to obstruct movement of the latter; and resilient means, operatively connecting said cover with said friction means, for causing said friction means to be yieldably moved into said operative relationship as an incident of moving said cover.

6. In a structure comprising a cabinet containing a phonograph: in combination, a closure for said cabinet movable into open and closed positions; a movably mounted carriage on said phonograph adapted to be driven and otherwise freely moved; means operable to obstruct the free movement of said carriage; and means, operatively connecting said obstructing means with said closure, for causing said obstructing means to be controlled according to the positioning of said closure.

7. In a phonograph having a carriage movable in relation to a record: in combination, a rod extending along the path of said carriage and having a non-circular cross section; a portion on said carriage embracing said rod and slid therealong by the movement of the carriage in its path; and means for turning said rod about its longitudinal axis to cause the rod to bear against said portion of the carriage, whereby to obstruct the carriage against movement in its path.

8. In a phonograph having a carriage movable in relation to a record: in combination, a support rod for said carriage turnable about its longitudinal axis and having a non-circular cross section; a portion of said carriage slidably fitting

a substantial portion of the circumference of said support rod; and means for turning said rod to cause the latter to bear against said portion of the carriage, whereby to obstruct the carriage against movement in its path.

9. In a structure comprising a cabinet and a phonograph within said cabinet including a translating device: the combination of a cover on said cabinet movable into open and closed positions; a mechanism associated with said translating device and operable to place and releasably hold the device into operative and inoperative conditions; an operative coupling between said mechanism and said cover causing the mechanism to be operated in response to a movement of the cover between open and closed positions, said coupling being placed into inoperative condition to free said mechanism from said cover in response to the terminal movement of the cover into open position; and means effective when said coupling is in inoperative condition to control said mechanism manually.

10. In a structure comprising a cabinet and a phonograph within said cabinet including a translating device: the combination of an openable and closeable cover for said cabinet; a carriage for said translating device included within said phonograph and movable with respect to said cover; a control means for said translating device mounted on said carriage and having reproducing and other positions; and means, arranged to connect said cover with said control means irrespective of the position of said carriage in its path, for moving said control means out of reproducing position as said cover is closed.

11. In a structure comprising a cabinet and a phonograph within said cabinet including a translating device: the combination of an openable and closeable cover for said cabinet; a movably mounted carriage included within said phonograph and supporting said translating device; a control means for said translating device mounted on said carriage and having operative and inoperative positions; movable means extending along the path of said carriage and operatively connected with said control means; and means, operatively connecting said movable means with said cover, for moving said control means out of operative position as an incident of closing said cover.

12. In a structure comprising a cabinet and a phonograph within said cabinet including a translating device placeable into operative and inoperative conditions: the combination of a closure for said cabinet movable between open and closed positions; manually operable conditioning means for said translating device having a position wherein said conditioning means extends into the path of said closure; and means, operatively connecting said closure with said conditioning means and controlled by the closure in the movement of the same into closed position, for moving the conditioning means out of the path of the closure.

13. In a structure comprising a cabinet and a phonograph within said cabinet including a translating device having operative and inoperative conditions: the combination of a closeable and openable closure for said cabinet; conditioning means for said translating device having a range of movement extending from the contour of said cabinet to a position wherein the conditioning means projects beyond said contour; and means connecting said closure with said conditioning means for moving said conditioning

means into a position within said contour upon the closing of said closure.

14. In a structure comprising a cabinet and a phonograph within said cabinet including a translating device having operative and inoperative conditions: the combination of an openable and closeable cover for said cabinet; a movably mounted carriage included within said phonograph and supporting said translating device; conditioning means for said translating device, mounted on said carriage and having a range of movement extending into the path of said cover; movable means extending along the path of said carriage and connected with said conditioning means; and means operatively connecting said movable means with said cover to cause said conditioning means to be moved out of the path of said cover as an incident of closing the cover.

15. In a structure comprising a cabinet and a phonograph within said cabinet including a translating device having operative and inoperative conditions: the combination of a closure for said cabinet movable between open and closed positions; conditioning means for said translating device manually movable into an outward position wherein said conditioning means projects beyond the contour of said cabinet; and means operatively connecting said closure with said conditioning means and restricting said conditioning means to positions within said contour when said closure is out of open position.

16. In a structure comprising a cabinet and a phonograph within the cabinet including a translating device having operative and inoperative conditions: the combination of a movable cover for said cabinet; a movably mounted carriage included within said phonograph and supporting said translating device; a member stationary relative to the directions of movement of said carriage; a manually operable conditioning means for said translating device; means operable to couple said carriage with said stationary member; and means, operatively connected with said cover, for concurrently operating said coupling means and conditioning means.

17. In a structure comprising a cabinet and a phonograph within the cabinet including a translating device having operative and inoperative conditions: the combination of a closure for said cabinet having open and closed positions; a movably mounted carriage included within said phonograph and supporting said translating device; a member stationary relative to the directions of movement of said carriage; means operable to couple said carriage with said stationary member; conditioning means for said translating device movable into a position wherein the conditioning means extends into the path of said cover; and means, operatively connecting said closure with said conditioning means and coupling means respectively and operated as an incident of moving the closure into closed position, for moving said conditioning means out of the path of said closure and for rendering said coupling means operative.

18. In a structure comprising a cabinet and a phonograph within the cabinet including a translating device having an inoperative condition and respective operative conditions for recording and reproducing: the combination of a closure for said cabinet having open and closed positions; a driving means for said phonograph; a carriage for said translating device connectable with said driving means and normally freely movable when disconnected therefrom; control means

for conditioning said translating device, having an inoperative position and respective operative positions for recording and reproducing and projecting beyond the contour of said cabinet when in at least one of its operative positions; means for respectively connecting and disconnecting the carriage with respect to said driving means as said control means is moved into operative and inoperative positions; and means, operative-

ly connecting said closure with said control means, for moving the control means from said one of its operative positions to the other of its operative positions as the closure is moved into closed position, and for moving said control means from said other of its operative positions to inoperative position as the closure is moved into open position.

HENRY S. CARLSON.
